DESIGN FOR A CHAIR CUSHION

James A. MacKay, Chicago, Ill., assignor to Ken-
lit Mfg. Co., Medford, Mass., a corporation of
Massachusetts

Application June 29, 1934, Serial No. 52,388

Term of patent 7 years

To all whom it may concern:

Be it known that I, JAMES A. MACKAY, a citizen of the United States, residing at Chicago, in the county of Cook and State of Illinois, have invented a new, original, and ornamental Design for Chair Cushions, of which the following is a specification, reference being had to the accompanying drawing, forming a part thereof.

In the drawing.—

Fig. 1 is a perspective view of a cushion em-

bodying this invention in the form and arrangement which it occupies in a chair;

Fig. 2 is an elevation showing two such arm cushions extended in the same plane as the attached back cushion, for more complete and exact illustration of the design.

I claim:

The ornamental design for a chair cushion substantially as shown and described.

JAMES A. MACKAY.
